UNITED STATES PATENT OFFICE

123,114

DESIGN FOR A COMBINED LAMP, TIMER, AND CONDIMENTS HOLDER FOR RANGES

Herbert M. Reeves, Kankakee, Ill., assignor to Florence Stove Company, Gardner, Mass., a corporation of Massachusetts

Application November 30, 1939, Serial No. 88,583

Term of patent 3½ years

To all whom it may concern:

Be it known that I, Herbert M. Reeves, a citizen of the United States, residing at Kankakee, in the county of Kankakee and State of Illinois, have invented a new, original, and ornamental Design for a Combined Lamp, Timer, and Condiment Holder for Ranges, of which the following is a specification, reference being had to the accompanying drawing, forming a part thereof.

Fig. 1 is a front elevation of a combined lamp, timer, and condiment holder for ranges, embodying my new design.

Fig. 2 is a plan view of the same.

Fig. 3 is a right elevation of the same.
The dominant features of my design reside in the portions shown in full lines.

I claim:

The ornamental design for a combined lamp,
timer, and condiment holder for ranges, substantially as shown and described.

HERBERT M. REEVES.
